CLOCK

Laurens Hammond, Evanston, Ill., assignor to
Hammond Instrument Company, Chicago, Ill.,
a corporation of Delaware

Application February 13, 1931, Serial No. 515,599

33 Claims.

(Cl. 58—26)

My invention relates generally to time-keeping devices and more particularly to mechanical speed governing means especially usable in combination with synchronous electric clocks.

Synchronous electric clocks have come into general use because of their simplicity, durability, quiet operation, and high degree of accuracy. These clocks generally comprise an ordinary clock gear train driven by a synchronous motor and, as at present on the market, have the pronounced disadvantage that they stop upon interruption of the supply of alternating current. Several means for overcoming this disadvantage have been proposed but have not come into general use because of their commercial impracticability, even though the demand for a clock which will not stop upon interruption of the supply of current is very great. In some communities interruptions occur at frequent intervals, due to electrical storms, shut-downs in the power generating stations, and disconnections in the transmission lines necessary for repairs and alterations. Even in communities where the supply of current to the consumer is only very rarely interrupted, the supply of current to the individual clock is frequently interrupted due to the accidental disconnection of the plug from the socket through which the clock receives current, blowing of the consumer's fuse, and intentional disconnection necessitated by changing the location of the clock on the owner's premises.

In one of the attempts to overcome the disadvantage of having the clock stop upon interruption of the supply of current, of which I am aware, it was proposed to add to a self-starting synchronous motor driven clock a complete spring motor driven clock mechanism which served as a standby movement to drive the hands of the clock upon interruption of the current, suitable clutch and stop devices being incorporated to cause operation of the clock by the standby movement upon interruption of the current supply to the synchronous motor. This attempted solution of the problem presents difficulties in manufacture, greatly increases the cost of the clocks, and is not entirely successful in operation because of the fact that a certain amount of time is "lost" each time the transfer is made from the synchronous motor drive to the spring motor drive.

Another attempted solution involved the provision of a synchronous motor drive and spring motor drive connected through differential gearing with the hands of the clock, the spring motor

drive being held against operation while the synchronous motor was in operation and vice versa. This attempted solution had the same disadvantages as enumerated above except that instead of "losing" time the clock would gain time. The reason for this gaining of time was that it always took a certain amount of time to stop one of the mechanisms and start the other, and hence there was a certain amount of overlap during which interval both mechanisms were operating, thus permitting the differentially movable member of the differential gearing to move twice its normal speed during this interval.

In the clock of the present invention there is no auxiliary clock movement. Generally, the clock comprises an induction motor geared to wind a spiral clock spring, the driving side of which is geared to a synchronous electric brake which acts in place of the escapement mechanism of an ordinary clock, and prevents the spring from unwinding at greater than a predetermined speed. The rotating part of the synchronous electric brake is also connected to a centrifugal mechanical speed governing mechanism, a pawl and ratchet mechanism preventing the spring from unwinding and rotating the induction motor backward when the current supply is interrupted. Inasmuch as the synchronous electric brake is ineffective to control the speed of operation during an interval of current interruption, the centrifugal governing mechanism is so constructed that it is at all times effective to take over the speed governing function.

It will be understood that power generating stations supplying so-called "time service," regulate the frequency of the current supplied so that the average frequency during any extended period of time will always exactly equal the nominal frequency. For example, in a station supplying current at a nominal frequency of 60 cycles per second, the frequency may vary between 57 cycles and 63 cycles per second. In a large, well-regulated station the range of variation may often be reduced to between 59.8 and 60.2 cycles per second. Occasionally, especially in the smaller power generating stations, the frequency will drop gradually to a very low value due to the sudden addition of a large load upon the generator, or in fact, the frequency may drop gradually from 60 to 0 if the generator is slowed down due to accident or for repairs.

It is essential, in providing a mechanical speed governor for use in connection with a synchronous electric clock or similar device, that it does

not interfere with the operation of the clock upon such normal variations in the frequency of the current supply, since ordinarily compensation is made for such variations by increasing or decreasing the generator speed above or below the nominal frequency for a sufficient period of time to bring the average frequency back to the nominal frequency. A further requirement of a mechanical speed governing mechanism for use in controlling the speed of a clock or similar device during current interruptions, especially when used in connection with a clock which is not self-starting, is that the mechanical governor maintains the speed so close to the nominal frequency that upon resumption of the current supply the synchronous motor will again fall into step, or that the speed of operation be periodically varied between frequencies above and below the nominal frequency so that at regular intervals the clock will be operating at exactly synchronous speed and will have an opportunity to fall in step when the current supply is resumed.

The mechanical speed governing mechanism of my invention operates upon the latter principle, namely, permitting the clock alternately to accelerate and decelerate between definite limits above and below the nominal speed.

In addition to the objects above pointed out, the objects of my invention are to provide an electric synchronous clock which

(1) Will operate at constant average speed during periods of current interruption;

(2) Will not require manual rewinding;

(3) Utilizes a synchronous electric brake to control its speed of operation when current is being supplied to it;

(4) Has a centrifugal continuously-rotating mechanical means automatically operable accurately to maintain the speed of operation of the clock at a predetermined average speed during periods of current interruption;

(5) Has means forming part of the centrifugal mechanism which prevents vibration and oscillation of the centrifugal member;

(6) Has means for rapidly decelerating the centrifugal mechanism when the latter has attained a predetermined maximum speed;

(7) Has a spring for rotating the synchronous brake and centrifugal means;

(8) Has means for compensating for variations in the driving power of the spiral spring;

(9) Has means for insuring substantially instantaneous deceleration of the centrifugal mechanism and for preventing the partial incomplete deceleration of said means;

(10) Has means for adjusting the centrifugal mechanism to vary the maximum speed thereof;

(11) Has a resiliently mounted centrifugal weight which is held stationary relative to its revolving support during normal operation;

(12) Has improved means for frictionally and resiliently connecting the centrifugal mechanism to its supporting shaft;

(13) Permits variation in the speed of operation of the clock in synchronism with a current supply of varying frequency without affecting the centrifugal governing mechanism;

(14) Has means for facilitating restarting of the clock upon resumption of the current supply; and

(15) Has means to prevent restarting of the clock when the supply of current is resumed after the spring of the spring motor has run down.

A further object is to provide an improved mechanical speed governing means.

A further object is to provide an improved centrifugal speed governing mechanism operable to cause the rotating part alternately to accelerate and decelerate between definite maximum and minimum limits and thereby maintain a predetermined average speed of rotation.

A further object is to provide means for rapidly decelerating the centrifugal speed governing mechanism from a predetermined maximum speed to a predetermined minimum speed.

A further object is to provide a synchronous electric clock which will operate during current interruptions, which is simple in construction and operation, and which may be economically manufactured.

Other objects will appear from the following description, reference being had to the accompanying drawings, in which

Fig. 15 is a graph showing the velocity characteristics of a clock incorporating my invention.

General construction

In order that the detailed description of the clock may be more readily understood, the general features of construction and an outline of the operation will be presented first.

The clock comprises three generally similar frame plates 20, 22 and 24. Studs 26, 28, 30 connect plates 20 and 22, and studs 32, 34 and 36 join plates 22 and 24. The clock is of course mounted in a suitable case, not shown, and has a face dial 38, an hour hand 40, minute hand 42, and second hand 44.

Referring to the diagram of Fig. 7, the clock comprises an induction motor having an induction rotor 64, which, through the gear train 76, 86, 90, 92, 98, 100, 104, 106, 110 and 112, rotates spring drum 114. The spring 118, the outer end of which is secured to the drum 114, has its inner end secured to the shaft 116, and through gear train 120, 122, 124, 126, 128, 130, 132, 134, 136 and 138, drives shaft 74. The toothed rotor 70 forms a synchronous brake in cooperation with the toothed poles forming part of a suitable mag-

netic field, and is rigidly secured to the shaft 74. Also secured to the shaft 74 is a mechanical speed governing mechanism, shown in Fig. 7 as comprising a weight 372 which is resiliently connected to a frame 352 carried by the shaft 74. A pawl 178 cooperates with the ratchet wheel 176 to prevent clockwise rotation thereof. The hands of the clock are driven from the train of gearing which connects the rotor 70 of the synchronous brake and the shaft 116.

In operation, the induction rotor 64, if unimpeded, would rotate at a speed several times as great as the rotor 70 of the synchronous brake and thus it will be effective to wind the spring 118 and maintain it wound. When the spring is thus wound, a force will be transmitted to the shaft 116 and hence through the train of gearing to the synchronous brake. Assuming that the synchronous brake has been set in motion at synchronous speed (which is accomplished manually), the induction rotor will, through the two trains of gearing and through the spring 118, continue to rotate the synchronous brake and also the centrifugal mechanism which is resiliently connected to the shaft 74 and rotatable therewith.

Upon an interruption of the supply of current, the spring 118 will of course tend to rotate the shaft 116 counterclockwise and the spring drum 114 clockwise. The clockwise movement of the spring drum 114 will, however, be arrested in a short time by the pawl 178, so that all of the remaining energy stored up in the spring 118 will be dissipated through driving the train of gearing shown at the right in Fig. 7, and the shaft 74 and all parts rotatable therewith. During the periods of current interruption, the synchronous brake is of course not effective to control the speed of rotation of the shaft 74. During this period, however, the centrifugal mechanism accomplishes this function, the pawl 178 arresting clockwise movement of the ratchet wheel 176 so that the spring 118 is effective to rotate shaft 116 and through the connecting gear train rotate the shaft 74.

As will hereinafter appear, the centrifugal mechanism, which includes the frame 352 and its resiliently mounted weight 372, governs the speed of rotation of the shaft 74 and performs all of the functions of a balance wheel or pendulum escapement mechanism, as well as several additional functions.

The induction motor and the synchronous brake

The coil 50, which is adapted to be connected to a suitable source of alternating current by conductors 52 and plug 54, is wound about the inwardly projecting ends of laminations 53, 55, 56, 57, 58 and 59 (Figs. 3, 4, 12, 13 and 14), which are secured to each other by bars 60 and to the frame plate 22 by bolts 62, 63. The laminations 56 and 58 are substantially E-shaped, the ends of the two lower horizontal portions of these laminations being shaped to form field poles for a hard steel rotor 64 of the induction motor, a diametrically opposite pair of these poles being shaded by having a plurality of copper rings 66 pressed thereover. The rotor of the induction motor could be made with induction bars, or could be a disc of cold rolled steel, but a hardened steel disc is preferred because of the greater torque which it is capable of developing. The term "induction motor" is used in the specification and in the claims to distinguish the motor, which comprises the rotor 64 and field lami-

nations 56, 58, from the spring motor, and the term should be construed broadly to define any self-starting motor capable of developing torque throughout a wide range of speeds. The laminations of the unshaded poles are preferably secured against vibration by bolts or rivets 68. The inner laminations 57, 59, of which there are several pairs, have diametrically opposite inwardly projecting portions 57' and 59' which form poles for the rotor 70 of the synchronous brake. These poles are toothed to register with the teeth formed upon the rotor 70, as shown in dotted lines in Fig. 3. A plurality of pairs of laminations 53, 55 are positioned between the laminations 56, 58 and 57, 59, respectively, forming spacers therefor.

The rotor 70 may be solid or may be formed of two or more identical laminations secured to a hub 72, the latter being non-rotatably secured to a shaft 74. The rotor 64 of the induction motor is pressed over a pinion 76 which is freely rotatable upon the shaft 74. The shaft 74 is rotatably mounted in suitable bearings formed in plates 78, 80 secured to frame plate 24 and bearing plates 82, 84 secured to frame plate 22. These bearing plates are made of a phenolic condensation product or similar material.

The gear trains and spring motor

As best shown in Figs. 4, 6 and 7, the pinion 76 is in mesh with a gear 86, which is secured on a sleeve 81 and freely rotatable upon a shaft 88, and has a pinion 90 secured thereto. The pinion 90 meshes with a gear 92 secured to a sleeve 94, which is rotatable upon a shaft 96. The opposite end of the sleeve 94 has a pinion 98 secured thereto meshing with a gear 100 which is rigidly secured to a shaft 102. The gear 100 carries a pinion 104 which meshes with a gear 106, the latter being freely rotatable upon a shaft 108 and carrying a pinion 110. The pinion 110 meshes with a gear 112 formed on the spring drum 114, the latter being mounted for free rotation upon the spring shaft 116. A spiral clock spring 118 has its outer end secured to the spring drum and its inner end secured to the shaft 116.

The above described gear train thus is adapted to transmit power from the induction rotor 64 to the spring drum to wind the same, or rather, in normal operation, to maintain the same wound. A similar gear train is utilized for transmitting the power of the spring to the synchronous brake. This gear train comprises gear 120 secured to the shaft 116 and meshing with pinion 122 secured to shaft 108. The pinion 122 is rigid with a gear 124, the latter meshing with the pinion 126, freely rotatable on the shaft 102. A gear 128 is fixed to the pinion 126 and meshes with a pinion 130, the latter being fixed to shaft 88. The opposite end of the shaft 96 has a gear 132 secured thereto, the latter meshing with a pinion 134 secured to the shaft 88. A gear 136, rigid with the pinion 134, drives a pinion 138 secured to the shaft 74. As previously stated, the rotor 70 is rigidly secured to the shaft 74. The last described gear train is thus adapted to transmit the driving energy of the spring 118 to the rotor assembly of the synchronous brake. The rotor 64 of the induction motor and the rotor 70 of the synchronous brake rotate in the same direction, and it will be noted that corresponding gears of the two trains are in each instance mounted on the same axis, and since the gear ratios are identical, each gear which is rotatable on a shaft will, during normal operation of the

clock, rotate in the same direction and at the same speed as the shaft upon which it is mounted. Thus there will be extremely little wear in the bearings of the gears and pinions which are rotatably mounted upon the shafts, the only bearings continuously subjected to wear being those of the rotatable shafts. By providing the gearing in this manner, I have in effect eliminated one-half of the bearings which would otherwise be necessary. Due to the improved bearings which I have provided for the ends of the shafts, the wear upon bearings has been greatly reduced and the clock mechanism made more durable. It will be understood that the only time when the gears which are rotatably mounted upon a shaft rotate relative to the shaft is during intervals of current interruption when the train of gearing between the rotor 64 of the induction motor and the spring drum 114 is stationary, and following an interruption when the spring is rewound.

The gearing ratio is such that the shaft 108 will rotate at one revolution per minute, and the second hand 44 may therefore be secured to the end of this shaft. The shaft 108 has a pinion 140 secured thereto which meshes with a gear 142 rotatably mounted upon a shaft 144. The gear 142 is rigidly connected to a pinion 148 which meshes with a gear 148 rotatably mounted upon the shaft 108. The latter gear is rigidly connected to a sleeve 150 surrounding the shaft 108 and at its end carrying the minute hand 42. The gear 148 is frictionally rotated with the shaft 108 by a spider spring 149 compressed between the pinion 140 and the side of the gear 148. The pinion 152 secured to the gear 148 meshes with a gear 154 secured to the shaft 144. The gear 154 has a pinion 156 secured thereto and projecting outwardly through the frame 20, the pinion 156 meshing with a gear 158 secured to the hour hand sleeve 160. It will thus appear that the time indication of the clock is taken from the rotation of the shaft 108.

The hands of the clock may be set in the usual manner by rotating a thumb nut 162 secured to a stem 164, the latter being rotatably mounted in the frame plates of the clock and having a pinion 186 secured thereto and meshing with the pinion 154.

A knurled starting thumb piece 168 is secured to a shaft 170, the latter being mounted for rotation and axial movement in the frame plates 22 and 24 and carrying a pinion 172, adapted to mesh with gear 132 when the thumb piece 168 is pushed inwardly. A spring 174 normally holds the pinion 172 disengaged from the gear 132. This thumb piece is used only in starting the clock, as will hereinafter appear.

The drum 114 of the spring motor has a ratchet wheel 176 secured thereto or formed integrally therewith. A spring pressed pawl 178 is engageable with the teeth of the ratchet wheel 176 to prevent clockwise (Fig. 7) rotation thereof. If desired, a so-called "silent pawl" may be substituted for the spring pressed pawl 178.

The centrifugal brake mechanism

The centrifugal brake mechanism shown in Figs. 4, 5, 7, 8 and 9, comprises a hub 354 which is freely rotatable upon the shaft 74 and which is rigidly secured in a frame 352. The frame 352 is preferably made of a light metal such as aluminum, and comprises arms 356 and 358 joined at their ends by a cross-piece 360, and arms 362 and 364 joined at their ends by an arcuate section 366. The extremity of the arm 356 is bent

outwardly to form a lug 368. A leaf spring 370 has one end riveted to the lug 368 and at its opposite end has a small weight 372 secured thereto.

5 An adjusting screw 374 passes freely through a suitable aperture in the spring 370 and is threaded in a lug 376 struck outwardly from the side of the cross-piece 360. The head of the screw normally holds the spring in the position shown in Fig. 8 with the weight 372 resiliently held against a stop lug 378 which is bent outwardly at the end of arm 358. Outward movement of the weight 372 under the influence of centrifugal force, is limited by a stop 380 bent outwardly from the cross-piece 360 and engageable with the spring 370 adjacent the weight 372.

20 The frame is secured against more than a limited degree of rotation relative to the shaft 74 by means of a wire spring 382. This spring passes through a suitable aperture formed in a lug 384 struck up from the arm 356 through a relatively large hole 386 formed in the shaft 74 and has its other end positioned in an L-shaped notch 388 formed in a lug 390 struck up from the arm 362. The spring is held against longitudinal movement by the lug 368 and a lug 392 struck up from the arm 362. The spring is bowed so that it normally pulls the frame 352 to the right (Figs. 4 and 5) so that the hub 354 presses against a washer 394 which is mounted on the shaft 74. The washer 394 is preferably made of a phenol condensation product or similar substance.

25 It will be noted that the hole 386 in the shaft 74 is of considerably larger diameter than that of the spring wire 382 so that the latter, and hence the frame 352, may pivot through a limited angle relative to the shaft 74, as indicated in Fig. 5a. Of course the frame 352 may move through a slightly greater angle relative to the shaft 74 than the spring wire 382 since the latter will bend slightly to permit such additional movement of the frame. The spring 382 thus serves as a means to cause a definite amount of friction between the frame 352 and the shaft 74 and also serves as a resilient driving connection between the shaft and the frame. The frame is statically and dynamically balanced for rotation at its normal speed, a suitable counterweight 396 secured to the arcuate section 366 being provided for this purpose.

30 35 It will be noted that the spring 370 extends a slight distance beyond the weight 372. This end portion of the spring is adapted, when the frame 352 is rotated above its normal synchronous speed, to contact with an arm 398 which is secured to a bushing 400 carried on the end of shaft 402. The shaft 402 is rotatably mounted in the frame plates 22 and 24 but is urged to rotate counterclockwise (Fig. 8) by a torsion spring 404, one end of which is anchored to the shaft and the other end of which is anchored to the frame 22, the spring thus maintaining the arm 398 against a suitable stop 406 struck from frame plate 24. The arm 398 is hardened and its end is sharpened as indicated in Fig. 8a. It is desirable that this edge be made very sharp and hard so that the tip 408 will, if it is revolving in a position to strike the extreme edge of the arm, engage and move the arm instead of striking the latter a glancing blow.

40 45 50 55 60 65 70 75 70 The arm 398 is hardened and its end is sharpened as indicated in Fig. 8a. It is desirable that this edge be made very sharp and hard so that the tip 408 will, if it is revolving in a position to strike the extreme edge of the arm, engage and move the arm instead of striking the latter a glancing blow.

Operation

Assuming that the plug 54 has been connected to a source of alternating current of regulated

frequency, the operation of the clock is as follows: As soon as a connection with the source is made, the rotor 64 of the induction motor, due to the rotating field formed by the shaded poles of the laminations 56, 58, commences rotating, and through the gear train between it and the spring drum 114 commences winding up the spring 118. The rotor 70 of the synchronous brake will be held stationary by the magnetic flux since its field is not rotating, but on the contrary its pole pieces have teeth which register with and attract the teeth of the rotor. The spring, even when fully wound up, is not sufficiently strong to move the rotor 70 of the synchronous brake out of its magnetically "locked" position. Thus, unless the synchronous brake is moved from its locked position, the induction rotor 64 would continue to operate until the spring 118 was fully wound up.

The user is instructed, after he has connected the plug 54 in a suitable socket, to push in and rotate the thumb piece 168 clockwise. When the thumb piece is pushed in, the pinion 172 connected to its stem 170 engages the gear 132 so that when the thumb piece is manually twirled, the shaft 74 and all parts connected therewith are rotated, the rotor 70 of the synchronous brake being forcibly moved out of its magnetically locked position. As soon as the rotor rotates at any appreciable speed, the poles of the synchronous brake do not exert any great magnetic attraction. This condition continues until the rotor attains synchronous speed. Manual rotation of the shaft 74 at much greater than synchronous speed is hampered by the engagement of extremity 370 of the weighted spring 370 with the arm 392, since at speeds substantially higher than synchronous speed the centrifugal force on the weight 372 will be sufficient to overcome the force of the spring 370 and cause the latter to move toward its stop 390.

As the rotor approaches synchronous speed its magnetic field exerts a powerful torque upon it, but unless the teeth of the rotor are in exact phase with the alternating current it will tend to pass right through synchronism. If, however, the teeth of the rotor are in exact phase with the alternating current at the time the rotor is at synchronous speed it will then continue to operate in synchronism. Unless some means are provided to dissipate energy at the instant that the rotor 70 arrives at synchronous speed, there is a probability that the rotor will not "fall into step." The theory and principles of the operation of the rotor with reference to its coming into synchronism are substantially the same as those of a similar rotor of a synchronous motor, such, for example, as is shown and described in Patent No. 1,719,805, granted to me on July 2, 1929. In the present construction, the frame 352 and all parts carried thereby constitute the inertia member and correspond to the inertia washer disclosed in said patent. It will be noted that the frame 352 is frictionally connected to the shaft 74 normally to rotate therewith by means of the frictional engagement of the hub 354 with the friction washer 394 caused by the bowed spring 382. The friction between these parts should be considerable, but should be small enough to permit relative motion between the parts when the rotor falls into step. The spring 382 has sufficient play in the hole 386 and is sufficiently pliable that it does not materially interfere with the utility of the frame 352 and parts carried thereby as an inertia means to

insure falling into step of the rotor 70 of the synchronous brake, but of course causes the frame 352 and associated parts to rotate with the shaft 74 except for such minor relative movement as is desirable to cause the rotor of the synchronous brake readily to fall into step and to prevent it from hunting.

Having brought the synchronous brake rotor 70 up to synchronous speed, it will continue to be driven by the spring 118 and will act as a nearly perfect governor to control the speed of unwinding of the spring in synchronism with the frequency of the alternating current supply. The rotor 64 constitutes a variable speed motor which is of the induction type. It is capable, however, of running at a speed several times the synchronous speed of the rotor 70, so that even though the rotor 70 is started substantially at the same time that the clock is connected to a source of alternating current, it will within a short time completely wind the spring 118, or at least will wind the spring to an extent where the torque from the spring tending to rotate the rotor 64 in a reverse direction is exactly equal to the torque developed by the rotor 64 when rotating at the same speed as the rotor 70. While the clock is thus operating the centrifugal impulse governing mechanism will operate idly, the weight 372 being held against the stop 373 by the leaf spring 370.

In Fig. 15, I have illustrated a velocity-time diagram in which the curve from A to B represents the speed of operation of the clock during normal operation while the synchronous brake is effective. Assuming that the nominal frequency of the current supply is 60 cycles per second, the velocity of rotation of shaft 74 of the clock will vary slightly above and below its synchronous speed for the nominal frequency in accordance with the minor frequency variations in the current supply. (For convenience, the angular velocity of the shaft 74 will hereinafter be expressed in units of such value that its numerical value will be the same as the current frequency which would, through the control of the synchronous brake, cause it to rotate at such velocity—e. g., when the frequency of the current supplied to the synchronous brake is 60 cycles per second the shaft 74 will have an angular velocity, or speed, of 60.)

While the frequency of the current supplied by well regulated power stations will seldom vary more than 1% above or below its nominal frequency, occasional sudden application of heavy loads or breakdown of one of the generators in the station may cause the frequency to drop considerably below the normal as indicated by the drop at C in the diagram of Fig. 15. Such a drop in frequency will not, however, affect the centrifugal governor, and unless the current is interrupted, the governor will not interfere with subsequent operation at super-synchronous speed necessary to "regain" the time "lost" as a result of the drop in frequency. While the frequency may occasionally drop greatly below the nominal frequency, it will seldom, if ever, greatly exceed the nominal frequency, since generator speeds greatly in excess of their normal speed, might readily result in damage to the prime movers, generators and other power station equipment.

It will be assumed that the generators are equipped with governors or other safety devices which will absolutely preclude them from rotating at a speed higher than that necessary to generate 65 cycle current. Under such condi-

tions, which are substantially those normally encountered, it will be desirable to provide a mechanical speed governing means for the clock which would not interfere with the normal operation of the clock under the control of the synchronous brake throughout a range of 0 to 65 cycles but which would be effective, upon a current interruption, accurately to control the speed of shaft 74 so that its average speed will be 60. It is of course desirable to accomplish this without the use of complicated electromagnetically operated brakes, clutches, etc., since such complications in the apparatus lead to inaccuracies and uncertainties in operation. The centrifugal impulse governor previously described possesses

15 these desiderata.

The centrifugal impulse governor operates upon the principle that a body starting at a given minimum velocity, accelerating at a constant rate to a predetermined maximum velocity, and decelerating at a constant rate to the said minimum velocity, will have an average velocity equal to the mean between the maximum and minimum velocities, irrespective of the rates of acceleration and deceleration. Referring to the diagram of Fig. 15, the average angular velocity of the shaft 74 will be maintained at 60 when rotating as represented by the broken line BD, even though rates of acceleration for individual cycles of acceleration and deceleration may differ. Thus the average angular velocity during the cycle EFGH will be the same as during the cycle IJKL even though, as is obvious, the rates of acceleration of these two cycles of operation differ considerably.

Upon an interruption in the supply of current to the synchronous brake, the main spring 118 will transmit its power through the gear train to shaft 74 and, since the spring is capable of exerting a torque greater than the counter-torque due to friction in the gear train, will accelerate the shaft 74 and all parts operatively connected therewith. Assuming that the current was interrupted at B (Fig. 15), the shaft will accelerate until it attains a speed of 65 represented by the point M (Fig. 15).

When the frame 352 attains the maximum speed of 65 the spring 370 will be flexed outwardly to the dotted line positions (Fig. 8) by centrifugal force acting on the weight 372, and its extremity 373 revolved in the path represented by the dotted circle 375. When traveling in this path the extremity will just strike the extreme end edge of the arm 398. This spring pressed arm and its connected parts have exactly sufficient inertia, and its spring 404 sufficient tension, that when the arm is thus struck by the end of spring 370, kinetic energy will be transferred from the spring 370 (and parts operatively connected therewith) to the arm 398 (and parts operatively connected therewith) in an amount exactly equal to that necessary to reduce the speed of the shaft to 55, the minimum velocity. This transfer of energy takes place substantially at the instant of impact, in a manner similar to that which takes place when a billiard ball strikes another squarely in line with its center of gravity. The spring 404 thus acts mainly as a means to receive the kinetic energy from the arm 398 and its shaft 400 and, after the impact, to return these 70 parts to normal position with the arm 398 resting against the stop 406 before the shaft 74 has made a complete revolution.

The arm 398 is so shaped and so positioned relative to the path of revolution of the extrem-

ity 373 of the spring 370 that it is practically impossible for the latter to strike the former a glancing blow. If the said extremity contacts only with the extreme end edge of the arm 398, the resultant forces are such that the spring will be outwardly (from the axis of shaft 74) flexed and thus be moved to a position where it will contact with arm 398 farther from the end edge of the latter. Thus the extremity 373 either properly hits the arm 398 or misses it entirely.

When the extremity 373 strikes the arm 398 the stop 380 limits its outward movement, thus precluding the possibility of the spring 370 being bent beyond its elastic limit. After striking the arm 398 the spring 370 and weight 372 would have a tendency to vibrate relative to the frame 352 were it not for the provision of the stop lug 378 which acts as a damper. The energy which 20 would otherwise set up vibration is quickly dissipated upon impact of the weight 372 against the stop lug 378. The possibility of the extremity 373 striking the arm 398 when the frame 352 is not rotating at its predetermined maximum speed is thus eliminated.

25 The predetermined maximum velocity (at which the arm 398 will be struck) may be changed with a very high degree of accuracy by adjustment of the screw 374. Changing the maximum velocity will of course result in a corresponding change in the average velocity.

It will be observed that as the main spring 118 becomes unwound its power decreases and the rate at which it can accelerate the centrifugal governing mechanism correspondingly decreases, but that this does not have any effect upon its governing or timekeeping qualities. Since the deceleration is very rapid, being nearly 30 instantaneous, the force of the main spring 118 is practically eliminated as a factor during this phase of the operating cycle.

Throughout the period of current interruption the centrifugal governing mechanism will repeatedly operate in the manner above described, and as diagrammatically illustrated in Figure 15. Upon resumption of the current supply, the synchronous brake will become effective as soon as its rotor 70 is accelerated to its synchronous speed, the frictional and resilient connection between the frame 352 and the shaft 74 aiding the rotor to fall into step. If perchance the rotor should not fall into step the first time it approaches synchronous speed, it will have innumerable additional opportunities to fall into step during the accelerative phase of subsequent cycles of operation of the centrifugal governing mechanism. It is improbable that the rotor will fall into step during the decelerative phase of the cycle because the deceleration occurs so rapidly.

60 The centrifugal governing mechanism, as above set forth, has a large number of advantages when used in combination with a synchronous electric clock, but obviously is useful in other timekeeping and speed governing mechanisms.

Modified centrifugal governing mechanism

In Figs. 10 and 11, I have illustrated a modified form of the centrifugal impulse governing mechanism. This mechanism operates upon substantially the same principles as the mechanism above described. It comprises a rotor shaft 47° having a head 204° secured at the end thereof, and having a bar 192° rotatably mounted on the shaft 75 but normally rotated therewith by means of the

wire spring 208^c, the ends of which project into openings 210^c formed in the bar 192^c and the mid portion of which engages in a slot formed in the head 204^c. The bar 192^c has a pair of arms 193 to which are secured a pair of leaf springs 196^c. Weights 200^c are secured a short distance inwardly from the free extremities of the leaf springs 196^c. The extremities of the leaf springs are adapted, when swung outwardly by centrifugal force, to engage the teeth 330 of an inertia wheel 332 which is rotatably mounted upon a shouldered stud 334. Assuming that the shaft 74^c rotates counterclockwise (Fig. 10), the teeth 330 will have substantially radial faces in position to be struck by the extremities of the leaf spring 196^c. The arms 193 are arcuately shaped so that their extremities form fixed stops for the leaf springs 196^c and thus hold the weights outwardly a slight distance beyond that which they would assume when revolving at their normal synchronous speed. The arms thus serve the same purpose as the stop 318 in the previously described embodiment, and serve as energy dissipating means to damp vibratory motion of the weights.

It will be understood that the mechanism shown in Figs. 10 and 11 is adapted to be substituted for that shown in Figs. 8 and 9, and that the shaft 74^c corresponds to the shaft 74 in the previously described embodiment. The operation of this mechanism is substantially the same as that of the mechanism of Figs. 8 and 9. There is sufficient friction between the wheel 332 and its mounting stud 334 that the wheel will quickly come to a stop after being struck by the extremities of one of the leaf springs 196^c, and be in a state of rest before the mechanism will have had an opportunity to accelerate sufficiently to cause the ends of the leaf springs again to strike the wheel. The maximum velocity of the mechanism may readily be adjusted by means of the screws 342. Adjustment of the maximum velocity will of course effect a corresponding variation in the average velocity. In this embodiment as well as in that previously described, the transfer of energy takes place substantially instantaneously upon the impact of the extremity of the spring 196^c with a tooth of the wheel 332, and therefore the amount of energy transferred from the rotating part of the mechanism to the wheel 332 is dependent substantially wholly upon the relative inertias of the parts. This embodiment as well as that previously described has the advantage that the centrifugal mechanism operates idly during normal operation and is only effective to control the speed of operation of the clock during intervals of current interruption. During the current interruptions the mechanism will make a slight noise which will serve the useful purpose of indicating that the current supply to the clock has been interrupted.

In the modified form of Figs. 10 and 11 as well as in the preferred construction, the spring 118 may be constructed so as to be capable of driving the mechanism for a period greatly exceeding in duration any usual current interruption. However, should the current be interrupted for a period sufficiently long to permit the spring 118 completely to unwind, and the clock to come to a stop, the clock will not again start upon resumption of the supply of current and will thus, by the fact that it is not going, indicate that it is showing the incorrect time. After such an unusual extended current interruption, it will be necessary to reset the hands of the clock and

75 restart it by manually twirling the thumb piece 168.

While I have illustrated and described the preferred embodiments of my invention, many modifications may be made without departing from the spirit of the invention, and I do not wish to be limited to the precise details set forth but desire to avail myself of all changes within the scope of the appended claims.

10 I claim:

1. In a time-keeping device, the combination of a shaft, a synchronous electric rotor rigidly secured to said shaft and a centrifugal governor rotatably mounted on said shaft, and a frictional and resilient driving connection between said governor and said shaft.

2. In a time-keeping device, the combination of a motor, a shaft driven thereby and means for controlling the speed of rotation of said shaft comprising a weight, a spring forming the sole means movable with respect to said shaft for securing said weight to said shaft, said weight being adapted to be moved outwardly from the axis of said shaft by centrifugal force, and movable impulse receiving means to impede rotational movement of said weight when the latter is moved a predetermined distance from the axis of said shaft.

3. In a time-keeping device, the combination of a coil adapted to be connected to a source of alternating current, a core for said coil having a plurality of pairs of poles, an induction rotor cooperating with one of said pairs of poles, an energy storing motor driven by said induction rotor, a synchronous brake driven by said energy storing motor and cooperating with the other of said pair of poles, and mechanical speed governing means for controlling the speed of operation of said energy storing motor when said synchronous brake is ineffective.

4. In an electrically controlled and operated timing device, the combination of a spring motor, electric motor means to wind said spring motor, gearing driven by said spring motor, an electro-magnetic mechanism driven by said gearing and maintained in synchronism with the alternations of electric current from a source of regulated frequency, a magnetic field producing means connected to said source for energizing both said electric motor means and said electro-magnetic mechanism, and continuously operating mechanical means for controlling the speed of operation of said spring motor upon interruption of the current supplied to said electro-magnetic mechanism.

5. Means for controlling the speed of operation of a rotating part comprising a synchronous brake connected to a source of alternating current, a centrifugal governing mechanism connected with the moving part of said brake to control the speed of operation of said rotating part upon interruption of the supply of current to said synchronous brake, and a resilient and frictional connection between said centrifugal governor and the moving part of said synchronous brake whereby the connection will serve as an energy dissipating means to aid in causing the synchronous brake to fall into synchronism with the source of alternating current and to minimize hunting of the synchronous brake.

6. In a time-keeping device, the combination of a synchronous electric brake having a rotatable part, power means for rotating said part of said brake, a member rotatable with the rotatable part of said synchronous brake, centrifugal

force operated means for moving said member relative to its axis of rotation, resilient means resisting the centrifugal force applied to said member, and an element positioned so as to be moved by said member when the latter is moved outwardly by centrifugal force resultant from rotation at a speed substantially greater than the synchronous speed of said synchronous brake, the inertia of said element being so great relative to the inertia of said member and the parts moving therewith that the latter will be rapidly decelerated to a velocity less than the synchronous speed upon impact of said member with said element and transmit a substantial portion of their kinetic energy to said element.

7. A speed governing mechanism for maintaining a constant average speed comprising a member, the speed of which is to be governed, means for repeatedly accelerating said member from a given minimum velocity, and means for repeatedly decelerating said member to said given minimum velocity whenever the member reaches a predetermined maximum velocity, the range of variation in the instantaneous velocity of the member being great compared with the range of variation of its average velocity.

8. A time-keeping device comprising a shaft, variable power means for rotating said shaft, a weight, means including a resilient element for securing said weight to said shaft eccentric of the axis of the shaft, and a peripherally notched wheel mounted for rotation at a point adjacent the path of revolution of said weight and adapted to receive a rotative impulse from said weight when the latter has attained a predetermined velocity of revolution, thereby to reduce the speed of rotation of said shaft.

9. A time-keeping device comprising a variable torque motor, a shaft connected to be driven thereby, a weight, means including a resilient element for securing said weight to said shaft eccentric of the axis thereof, a peripherally notched wheel, an adjustable pivotal support for said wheel, and means moved by said weight and engageable with said wheel when said shaft is rotating at a predetermined speed, thereby to impart to said wheel a portion of the kinetic energy of rotation of said shaft and parts rotating therewith.

10. A time keeping mechanism comprising motor means, a member mounted for movement by centrifugal force and revolved by said motor, and means for rapidly dissipating a predetermined substantial portion of the kinetic energy of said member whenever it attains a predetermined speed of revolution, said means being of such mass and construction, relative to the effective driving force of said motor means and the rotary moment of inertia of said member, that said means will be effective to reduce the speed of said member to a velocity such that it will take a number of revolutions of the latter to accelerate to a speed at which said means again becomes effective.

11. A time keeping mechanism comprising motor means, a member mounted for movement by centrifugal force and revolved by said motor means, means for rapidly dissipating a predetermined substantial portion of the kinetic energy of said member whenever it attains a predetermined speed of revolution, and means for damping vibratory movement of said member.

12. A time keeping mechanism comprising motor means, a member mounted for movement by centrifugal force and revolved by said motor, and

means for rapidly dissipating a predetermined substantial portion of the kinetic energy of said member whenever it attains a predetermined speed of revolution, said means comprising an element of appreciable inertia movably mounted in the path of movement of said member, the torque of said motor means, the rotary moment of inertia of the means driven thereby including said member, and the energy dissipating capacity of said means being so correlated that a number of revolutions of said member will be required for said member to accelerate from the speed to which it is reduced by said energy dissipating means to said predetermined speed.

15. 13. A time keeping mechanism comprising motor means, a member mounted for movement by centrifugal force and revolved by said motor means, means for rapidly dissipating a predetermined substantial portion of the kinetic energy of said member whenever it attains a predetermined speed of revolution, said means comprising an element of appreciable inertia, and resilient means to hold said element in the path of revolution of said member when the latter is revolving at its said predetermined speed.

14. A time keeping mechanism comprising a motor, a member mounted for movement by centrifugal force and revolved by said motor, a spring opposing such movement of said member, and means for rapidly dissipating a predetermined substantial portion of the kinetic energy of said member whenever it attains a predetermined speed of revolution, said means comprising an element having a surface normally in a plane passing through the axis of revolution of said member.

15. A time keeping mechanism comprising a spring motor, a member mounted for movement by centrifugal force and revolved by said motor, resilient means opposing the action of centrifugal force on said member, means to vary the force exerted by said resilient means, and means for dissipating a predetermined substantial portion of the kinetic energy of said member when the latter attains a predetermined maximum velocity.

16. A time keeping mechanism comprising a spring motor, a member mounted for movement by centrifugal force and revolved by said motor, resilient means opposing the action of centrifugal force on said member, means to vary the force exerted by said resilient means, means for dissipating a predetermined substantial portion of the kinetic energy of said member when the latter attains a predetermined maximum velocity, and means to damp vibration of said member.

17. In a time keeping device, a shaft having a hole passing diametrically therethrough, a frame rotatably mounted on said shaft, said frame having lugs thereon spaced from said shaft, a friction washer on said shaft between said frame and the hole in said shaft, and a resilient wire secured to said lugs and passing through said hole, said wire being bowed to draw said frame against said friction washer.

18. In a time keeping device, the combination of a shaft, a frame rotatably mounted on said shaft, a friction member on said shaft, and a single spring cooperating with said frame and shaft and operative resiliently to connect said frame to said shaft for conjoint rotation, to hold said friction member on said shaft and to hold said frame against said friction member.

19. In a time keeping device, the combination

of a shaft having a diametrical hole therein, a member rotatably mounted thereon, and a resilient wire of appreciably smaller diameter than said hole and passing therethrough, the ends of said wire being secured to said member, whereby said spring forms a resilient lost motion connection between said shaft and said member to permit limited relative rotative movement therebetween.

20. In a centrifugal governor for maintaining the speed of rotation of a member at a substantially constant predetermined average value despite a variation in the value of the driving force, a movable centrifugal element adapted to move outwardly from its axis of rotation upon an increase in speed, a normally stationary stop adapted to be struck when said centrifugal element moves outwardly to a position corresponding to a velocity considerably in excess of said predetermined average value to be maintained, and mounting means for said stop permitting the stop to move away under the influence of the stroke and thereby rob the rotating system in a single impact of an appreciable amount of its total kinetic energy of rotation.

21. In combination, a centrifugal governor for maintaining the speed of rotation of a member at a substantially constant predetermined average value despite a variation in the value of the driving force, said governor comprising a movable centrifugal element adapted to move outwardly from its axis of rotation upon an increase in speed, a normally stationary stop adapted to be struck when said centrifugal element moves outwardly to a position corresponding to a velocity considerably in excess of said predetermined average value to be maintained, mounting means for said stop permitting the stop to move away under the influence of the stroke and thereby rob the rotating system in a single impact of an appreciable amount of its total kinetic energy of rotation; and an independent electro-magnetic governing mechanism for limiting the speed of said rotary member to said predetermined average value, said mechanism being operable to maintain said governor at a speed at which said element will not strike said stop.

22. In combination, a centrifugal governor for maintaining the speed of rotation of a member at a substantially constant predetermined average value despite a variation in the value of the driving force, a movable centrifugal element adapted to move outwardly from its axis of rotation upon an increase in speed, a normally stationary stop adapted to be struck when said centrifugal element moves outwardly to a position corresponding to a velocity considerably in excess of said predetermined average value to be maintained, mounting means for said stop permitting the stop to move away under the influence of the stroke and thereby rob the rotating system in a single impact of an appreciable amount of its total kinetic energy of rotation, and a second governor normally operable to maintain said member at substantially said predetermined average speed, said second governor being constructed while operative never to permit said member to attain the said predetermined maximum speed.

23. In combination with an electrically wound clock mechanism, a synchronous brake rotor forming the escapement mechanism thereof, and a centrifugal speed governing mechanism rotating with said rotor and effective upon discontinuance of the operation of said synchronous brake

70 rotor to control the speed of operation of said clock mechanism.

24. A timing device comprising a mechanical motor, a time movement connected so as to be operated by said motor, a non-self-starting synchronous motor having its rotor connected in reversible driving relation with said movement, and a speed responsive mechanical governing device connected in driving relation with said movement, the latter becoming effective at a speed slightly above the normal speed of the movement, as determined by the speed of the synchronous motor, to momentarily reduce the speed slightly below normal.

15 25. A timing device comprising a mechanical motor, a time movement connected so as to be driven by said motor, and a pair of speed governing devices for said movement, one of said governing devices comprising a non-self-starting synchronous motor having its rotor connected in driving relation with said time movement for causing the time movement to operate at its normal rate of speed when the synchronous motor is operating as such at its synchronous speed, 20 the other governing device comprising a centrifugal speed checking device connected in driving relation with said movement and adjusted to become effective when the speed of the time movement is slightly above normal to momentarily reduce the speed to slightly below normal, the latter governing device serving to maintain the average speed of the time movement at approximately its normal value when the first mentioned control device is ineffective.

30 26. A timing device comprising a spring motor, a time movement connected to be driven by said spring motor, a pair of rotary speed governing devices for said time movement, both continuously connected in reversible driving relation therewith, one of said devices comprising a synchronous motor effective when energized at its normal frequency to maintain the rate of the time movement correct, and the other device comprising a centrifugal speed checking device effective when the synchronous motor is deenergized to maintain the average rate of the time movement substantially correct, said centrifugal speed checking device being of a type which may be driven at speeds considerably above and below the average speed which it is capable of maintaining, without having any speed controlling effect whatsoever upon the means driving it.

40 27. In a governing mechanism for maintaining a member at a constant average velocity, the combination of a rotating member, the velocity 45 of which is to be maintained at a given average velocity, a pivoted element positioned adjacent said member, a part movable outwardly from the axis of rotation of said member under the influence of centrifugal force, resilient means 50 resisting such movement of said part, yielding means to hold said element in the path of movement of said part when the latter has moved outwardly a predetermined extent, said part being adapted to engage said element when the former reaches a predetermined velocity which is 55 considerably in excess of the average velocity to be maintained, and yieldable means to rotate said member.

60 28. In an electrically wound clock, the combination of a synchronous rotor connected to the clock so as to form an escapement mechanism therefor, and a centrifugal governing mechanism 65 rotated with said rotor, said mechanism being

ineffective to perform its function when said rotor is operating at synchronous speed.

29. In a time-keeping device, the combination of driving means, an electric synchronous brake driven thereby, said brake having a rotor, a centrifugal speed governing mechanism having a rotating part, said mechanism being ineffective to perform its function while said synchronous brake is effective, and a resilient and frictional driving connection between said rotor and said rotating part.

30. In a time-keeping device adapted to be operated and have its speed controlled from a source of alternating current of regulated frequency, the instantaneous frequency of which may vary but the average frequency of which is constant with a high degree of accuracy, a non-self-starting synchronous motor connected to said source, said motor normally operating as a brake, a rotary centrifugal governor of a type which maintains a constant average velocity while permitting wide fluctuations in instantaneous velocity, a non-slipping driving connection between said synchronous motor and said centrifugal governor, electric motor means to drive said synchronous motor and said governor under normal conditions while current of regulated frequency is being supplied from said source, and energy storing means connected to drive said synchronous motor and governor upon interruption in the supply of current of regulated frequency from said source.

31. In a time-keeping device adapted to be operated and have its speed controlled from a source of alternating current having its cumulative frequency regulated by a time standard, a synchronous motor connected to said source and operable as a brake, a rotary centrifugal governor of a type which maintains a constant average velocity while permitting wide fluctuations in

instantaneous velocity, means interconnecting said synchronous motor and governor to cause the same to rotate together at a predetermined average speed determined by said synchronous motor during the time while current is being supplied from said source and determined by said governor during periods of interruption in the supply of current from said source, and means for mechanically driving said synchronous motor and governor.

32. In combination, an induction rotor, an energy storing and releasing motor operatively connected thereto, a synchronous brake rotor mounted adjacent and coaxial with said induction rotor and connected to be driven by said energy storing and releasing motor, and common means for producing a magnetic field for both of said rotors.

33. A clock comprising a time movement, a spring for driving said movement, an alternating current motor device for winding said spring and controlling the rate of said movement, said motor device comprising a single phase field element having parallel magnetic paths, one path producing a rotating magnetic field and the other path producing a pulsating magnetic field, a self-starting rotor element within the influence of the rotating magnetic field connected to wind the spring, a non-self-starting synchronous rotor element within the influence of the pulsating field connected to the time movement for synchronously restraining the time movement to operate at its correct speed, and a centrifugal governor device driven with said time movement and acting in opposition to the accelerating influence of the spring motor for intermittently reducing the rate of the time movement from above to below normal when the synchronous motor is deenergized.

LAURENS HAMMOND.
